BOX

Martin J. McClure, El Paso, Ill.

Application March 30, 1935, Serial No. 13,856

1 Claim. (Cl. 229—33)

My invention relates to improvements in boxes for strawberries and other small berries and fruits. At present these boxes are relatively expensive and are made up of wood and packed flat so that the user must dampen and form them up to shape himself. In this process quite a percentage of the boxes are cracked or broken so that they cannot be used, and the law prevents their use more than once so that the boxes represent quite an expense and loss to the berry grower.

With the above facts in mind it is the prime object of this invention to provide a box of simple, inexpensive and conveniently used form made up of heavy paper or light cardboard in a scored flat blank of proper shape and size so that it may be readily bent up and fastened to shape and with the material, paper or cardboard, waxed, paraffined or otherwise suitably impregnated to be moisture proof and capable of being washed, cleaned or sterilized for use more than once.

Another object is to provide a box of this kind having cover or handle tabs or flaps formed on the blank so as to cover the berries in the box or to act as handles for raising or carrying the box. A further object is to provide a box of this kind having a plurality of ventilating apertures in its sides to allow the free circulation of air through the berries and prevent spoilage.

With these and other objects in view the invention resides in the novel construction and arrangement of parts as hereinafter fully set forth and claimed, reference being had to the accompanying drawing wherein:

Figure 1 is a plan view of the blank from which the box is formed.

Figure 2 is a perspective view of a box formed up from the blank of Figure 1.

Figure 3 is a fragmental plan view of a blank having cover and handle tabs.

Figure 4 is a perspective view of a box formed up from the blank of Figure 3.

Referring now with more particularity to the drawing, in carrying out my invention I provide a flat rectangular blank 5 of heavy paper or light cardboard having sufficient stiffness to serve its purpose and waxed, paraffined or otherwise impregnated to be water and moisture proof. This blank 5 may be of any size and shape according to the size, capacity and shape of the box to be formed therefrom and as here shown is square with a central square bottom portion 6, opposite sides or side flaps 7 and intervening sides or side flaps 8 hereinafter termed ends or end flaps for convenience in description. Fastening flaps 9

are extended from the sides 7 filling out the corners of the blank but are separated from the ends 8 by slits 10 extending inward to the corners of the bottom portion 6. The junctions between the bottom 6, sides 7, ends 8 and fastening flaps 9 are all scored or otherwise marked off as shown at 11 so that the blank will bend easily at these points.

To make up the box indicated at 12 in Figure 2 from this blank 5 the fastening flaps 9 are first bent up from the sides 7 and then these sides are bent up at right-angles to the bottom 6. The ends are then bent up outside of the flaps 9 and small paper fasteners or staples 13 of conventional form are placed through these ends and flaps as shown holding the sides and ends upright and square as will be readily understood. These forming operations are readily and rapidly performed and the stapling may be done either by hand or by any of the small hand operated machines now on the market. Since the fastening flaps 9 meet at their inner ends 14 a smooth surface is provided around both the outside and inside of the box 12 so that the berries will not be bruised when packed in the box and so that adjacent boxes in a crate will not catch or hang on each other.

The sides 7 have a plurality of small ventilating apertures 15 both near their upper and lower margins thus allowing free circulation of air through the berries and preventing spoilage to a great extent. Since the box material is water proof the boxes may be washed, cleaned, and if necessary sterilized and used over and over again. Of course, the box material is selected to have the proper resiliency to bend up easily to shape without breaking or cracking.

In the blank shown in Figure 3 the bottom 6a, sides 7a, ends 8a and flaps 9a are all of the form above set forth but triangular cover or handle flaps or extensions 16 are extended from the outer margins of the sides and ends. These flaps 16 have their points or apices 17 directed outward and the blank is scored along the junction of the flaps with the sides and ends as shown at 18. The box 12a is formed up from this blank 5a exactly as set forth hereinbefore but the flaps 16 may be bent inward to cover the box when the berries are placed therein, or as shown in Figure 4 the flaps may extend straight upward from the margins of the box to act as handles for carrying the box and to add to the appearance. The shape of the flaps 16 is such that when folded over atop the box they will just nicely close the same as will be understood. Apertures 20 are 55

formed near the points 17 of the flaps 16 to act as finger holes for carrying the box, to receive strings for tying up or hanging the box for display and for ventilation purposes when the box is covered.

5 The advantages of the box thus formed over the usual wooden box will be readily apparent from the foregoing and while I have herein set forth a certain preferred embodiment of my invention, it is understood that I may vary from 16 the same in minor structural details, so as best to construct a practical device for the purpose intended, not departing from the spirit of the invention and within the scope of the appended claim.

15 I claim:

In a device of the kind described, a box made up from a blank of cardboard impregnated against moisture and including a bottom, sides turned upward from the bottom, ends turned upward from the said sides and disposed within the ends, staples 5 securing the ends and fastening flaps together, and the said sides having ventilating apertures near their upper and lower margins, and triangular handle and cover flaps extended at their 10 bases from the upper margins of the sides and ends and meeting precisely at the center so as to completely close the box, the said flaps having their apertures near their free ends.

MARTIN J. MCCLURE. 15
